Primary Examiner — Richard Kearney*Assistant Examiner* — Michael Hoffman(74) *Attorney, Agent, or Firm* — MUNCY, GEISSLER,
OLDS & LOWE, P.C.(57) **CLAIM**

I claim the ornamental design for a fluid changing device, as shown and described.

DESCRIPTION

FIG. 1 is a top, front, and right perspective view of a fluid changing device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate portions of the fluid changing device which form no part of the claimed design.

1 Claim, 7 Drawing Sheets(56)
